(57) **CLAIM**

I claim the ornamental design for a runway light, as shown and described.

DESCRIPTION

FIG. 1 is a right side perspective view of an embodiment of the present invention;

FIG. 2 is a front elevation view of the embodiment shown in FIG. 1;

FIG. 3 is a rear elevation view of the embodiment shown in FIG. 1;

FIG. 4 is a top plan view of the embodiment shown in FIG. 1;

FIG. 5 is a bottom plan view of the embodiment shown in FIG. 1;

FIG. 6 is a right side plan view of the embodiment shown in FIG. 1; and,

FIG. 7 is a left side plan view of the embodiment shown in FIG. 1.

The broken lines are shown for illustrative purposes only and form no part of the claimed design.
